United States Patent Office.

WILLIAM WALLACE GOODWIN, OF CAMDEN, NEW JERSEY.

Letters Patent No. 76,908, dated April 21, 1868; antedated November 5, 1867.

IMPROVEMENT IN DRY GAS-METERS.

The Schedule referred to in these Letters Patent and making part of the same.

TO ALL WHOM IT MAY CONCERN:

Be it known that I, WILLIAM WALLACE GOODWIN, of the city of Camden, county of Camden, and State of New Jersey, have invented a new and useful Improvement in the Dry Gas-Meter; and I do hereby declare that the following is a full, clear, and exact description of the construction and operation of the same, reference being had to the accompanying drawings, making a part of this specification, in which—

Figures 1 and 2 are plan views of the said improvement applied, and

Figure 3 a vertical section of the same.

In the manufacture of dry gas-meters it has become a matter of necessity to have some more reliable provision against the fraudulent consumption of the gas effected by reversing the relative points of connection of the meter with the supply and discharge-pipes, and thus avoiding a registration of the same. Several devices have been invented and applied for the purpose, which effect the object in a greater or less degree, in proportion to the varying conditions of the meter in respect to adhesions from the deposits of coal-tar about the joints of the devices, and to the varying pressure of the gasometer.

The object of my improvement is to afford a more perfectly effectual and reliable device for stopping and starting the flow of gas through the meter, when the direction of the current is changed by reversing the meter, as stated, and that will not be prevented either by the deposits of coal-tar or the variations in the pressure of the gasometer, from acting promptly for the purpose.

My invention consists in the construction and application of a device whereby the orifice in the plate through which the current passes to or from the valves will be either entirely closed or fully opened thereby, in accordance with the relative positions of the meter between the supply and the discharge-pipes, substantially as hereinafter described.

Referring to the drawings, A B is the lever, C the disk, and D the spring of the new device; E, the orifice, through which the gas enters and reaches the outlet-valves F' F'; G, the usual rotatory shaft, which operates the valves F F'; and H H' sections of the usual flag-staffs, which, through the ordinary jointed arms, (indicated by the dotted lines v,) give the necessary rotary motion to the shaft G.

Construction.

The lever A B is attached, in a horizontal position, to a plate, I, (which is fixed to the usual top-plate, J, of the meter,) by means of a pivot, k; which serves as its fulcrum, and to one of its arms B the disk C is secured by means of a vertical spindle, c', which is fixed in the centre of the disk C, and extends upward through a roomy hole in the end of the arm B of the said lever A B, while at the end of the other arm, A, there is a fixed stud, a', which carries a light, tilting, stop-lever or click, l, over which an arm, m, (which is fixed on the crank so as to project horizontally from the shaft G,) passes around freely and over l by tilting it, when the shaft G is rotated in the legitimate direction indicated by the arrow w in fig. 1. On the lever A B there is fixed another small stud, a'', in which one end of the bent spring D is fixed, while the other end of said spring is fixed in a stud, v', on the plate I.

The length of the arm B from the centre of the fulcrum-point K to the centre of the disk-spindle c' in its end, is exactly equal to the distance which is between the said fulcrum-pivot k and the centre of the orifice E; and the range of the end of the arm A of the said lever, between the stud v' and the step g' of the shaft G, is made just sufficient to allow the disk C to be alternately brought concentrically over the orifice E, as shown in fig. 2, or entirely away from it, as shown in fig. 1. The disk C is a thin piece of sheet metal, bent so as to be concave on its under side, as shown in fig. 3.

Operation.

The action of the spring D upon the stud a'' keeps the disk C in the position shown in fig. 1, while the gas flows in the legitimate direction through the meter, as indicated by the arrows thereon, but, when the meter is reversed in respect to the supply and discharge-pipes, an immediate change is produced in the movement of the bellows-disks, (not shown in the drawings,) and consequently a reverse movement of the flow of gas through

the meter, until the arm *m* on the rotating shaft *G* abuts against the short end of the click or tilting stop-lever *l*, and forces the arm *A* of lever *A B* around before it, and compressing the spring *D* until the said arm is brought into contact with the step *g'*, and thus the rotary motion of the shaft *G* arrested, the disk *C* having at the same time been brought concentrically over the orifice *E*, and thus being held more closely upon the plate *I* by the pressure of the gasometer, effectually preventing any further flow of the gas down through said orifice, (see figs. 2 and 3;) but, as soon as the meter is again reversed in respect to the supply and discharge-pipes, the pressure of the gas lifts the disk *C* sufficiently to afford a current, and thus allow the bellows-disks to move and give a rotary motion in the proper direction to the shaft *G*, which, carrying the arm *m* with it, consequently allows the spring *D*, by its reaction, to move the lever *A B*, with the disk *C*, back to its original position, thus entirely removing the said disk away, and leaving the orifice *E* wholly unobstructed, as seen in fig. 1.

The boundary edge only of the lower side of the disk *C* being in contact with the plate *I*, and being also very thin, a sufficient amount of adhesion to prevent its being lifted by the pressure of the gas in the meter can never take place when the orifice *E* is closed; and, however long a time the meter may have been in action in the legitimate manner, the pressure of the gas upon the bellows-disks, if the meter be reversed, will always be greatly more than necessary to overcome any adhesion that may then exist between the disk *C* and plate *I*, and will cause it to be promptly moved from the position beside the orifice *E*, as shown in fig. 1, to the position shown in fig. 2, closing the orifice.

It will therefore be seen that this device will be perfectly effective and reliable for stopping the flow of gas through the meter when the legitimate direction of the current is changed by reversing the meter, as stated, and that any deposits of coal-tar, or variation of the pressure of the gasometer or fountain-head of supply, will not prevent the device from acting promptly in either accurately closing or fully and certainly opening the orifice through which the current of gas legitimately passes through the meter.

I am aware that a hinged valve, inclined planes, and butterfly-valves have been applied to dry gas-meters, so as to close and open the orifice of supply or discharge, as the case may be, but neither of these devices effects a full and unobstructed opening of the orifice, which is a matter of the highest importance, and is fully attained by my invention.

Having thus fully described my invention, and what I believe to be the best mode of constructing and operating the same, what I claim as new, and desire to secure by Letters Patent, is confined to the following, viz:

I claim the application, to a dry gas-meter, of a device or combination of devices whereby the orifice in the plate through which the current of gas passes to or from the valves, will be either entirely closed or fully opened thereby, in accordance with the relative positions of the meter between the supply and discharge-pipes, as described, the said device or combination of devices being constructed and operated in the manner herein described, or in any other manner that will produce the same effect.

WM. WALLACE GOODWIN.
